FLUID TIGHT CLOSURE MEMBER FOR WASHER DRUMS

Filed June 11, 1924

UNITED STATES PATENT OFFICE.

HARRY W. MITCHELL, OF CLEVELAND, OHIO, ASSIGNOR TO G. F. MITCHELL & SON, A PARTNERSHIP COMPOSED OF GEORGE F. MITCHELL, GEORGE R. MITCHELL, AND HARRY W. MITCHELL, OF CLEVELAND, OHIO.

FLUID-TIGHT CLOSURE MEMBER FOR WASHER DRUMS.

Application filed June 11, 1924. Serial No. 718,290.

This invention relates to fluid tight closure members for washer drums, such as employed in washers of the type in which a fluid tight rotary drum forms the container 5 for the cleansing liquid and the articles to be cleansed.

In washers of the character above referred to an opening is provided in the peripheral wall of the drum through which access may 10 be had to the interior of the drum for insertion of the clothes to be washed and for the removal thereof after the washing operation, and it is necessary that the opening be provided with a fluid tight closure member 15 which will not permit leakage of liquid when the closure member passes beneath the body of liquid in the drum during rotation. The present invention has for its object to provide a closure member which will effectively seal the opening and which can be 20 readily removed to obtain access to the interior of the drum.

A further object is to provide a closure member which will not be loosened by pressure from within the drum, and which is so mounted upon the wall of the drum that internal pressure particularly that due to the weight of the liquid as the closure passes beneath the same will act to press the closure 25 member against its seat.

With the above and other objects in view the invention may be said to comprise the device illustrated in the accompanying drawings hereinafter described and particularly set forth in the appended claims, together with such variations and modifications thereof as will be apparent to one skilled in the art to which the invention appertains.

Reference should be had to the accompanying drawings forming part of the specification, in which Fig. 1 is a top plan view showing the closure member secured in place in the opening of the drum. Fig. 2 is a fragmentary transverse section through the closure member and showing a portion of the cylindrical wall of the drum in which the opening is formed, this view being taken on line 2-2 of Fig. 1. Fig. 3 is a fragmentary longitudinal section on an enlarged scale taken on line 3-3 of Fig. 1. Fig. 4 is an end elevation of the drum, this view being on a considerably smaller scale than the other views. Fig. 5 is a transverse sec-

tion on an enlarged scale through a portion 55 of the sealing ring.

Referring to the accompanying drawings, the closure member forming the subject matter of the present invention is designed for use with a washer cylinder of the rotary type, which is mounted for rotation upon a horizontal axis, and forms a fluid tight container for both the cleansing liquid and the articles to be cleansed.

As shown in Figs. 2 and 3, the drum is provided with an imperforate cylindrical wall formed of sheet metal and closed at its ends by suitable heads 2. In order to provide convenient access to the interior of the drum the cylindrical wall of the drum is provided with an opening and the sheet metal at the edge of the opening is rolled back upon itself to provide a tubular stiffening bead 3 within which there is enclosed a rubber filler ring 4 which serves to strengthen the bead and to prevent distortion thereof. The opening in the cylindrical wall of the drum is closed by means of a one-piece sheet metal closure member which has a body portion 5 of exactly the same size as the opening and adapted to fit therein, the body portion 5 having a curvature corresponding to the curvature of the cylinder, so that the outer surface of the closure member conforms to the surface of the cylinder.

Around the edge of the closure member there is an inturned flange 6 which when the closure member is in place in the opening fits within the inner edge of the stiffening bead 3, the inturned flange 6 having an outturned edge flange 7 which is stiffened at its outer edge by a reversely folded portion 8, the outwardly extending flange 7 underlying the stiffening bead 3 throughout the extent thereof. A gasket 9 in the form of a rubber ring is secured to the outwardly extending flange 7 of the cover and serves to seal the joint between the marginal portion of the cover and the beaded edge of the opening. The gasket 9 is provided with a groove 10 extending outwardly from the inner side thereof and of sufficient depth to receive the entire flange 7, so that the gasket 9 may be permanently secured upon the flange 7. The outer face of the gasket 9 is adapted to be pressed into concave form to conform to the tubular bead 3 when the closure member is clamped in place and the

inner portion of the groove 10 is enlarged to provide a cavity 11 upon the outer side of the flange 7 whereby the gasket is made more elastic so that it may readily conform to the form of the bead 3 and whereby a greater play is permitted between the stiffening bead 3 of the drum wall and the marginal flange 7 of the closure member. The opening in the wall of the drum is elongated in the direction of the axis of the drum and extends to adjacent the heads of the drum, the sides thereof being substantially straight and the ends rounded. At intervals around the opening wear plates 12 of somewhat harder and stiffer material than that forming the wall of the drum are riveted to the drum and these plates are provided with arched portion 13 overlying the bead 3 at the edge of the opening, said arched portions 13 being tapered toward the ends of the plates to provide wedge surfaces for engagement with clamping members carried by the cover. Clamping members 14 are mounted upon the outer side of the cover adjacent the edge thereof and arranged in such a manner that when the cover is in place one of the clamping members 14 will be opposite each of the wear plates 12. The clamping members 14 are carried by pivots 15 which connect the clamps 14 with stamped sheet metal base members 16 riveted upon the outer surface of the closure member. Each of the clamping members 14 is provided with an outwardly projecting thumb piece 17 by means of which the clamping members may be readily turned into engagement with the wedge portions 13 of the wear plates or inwardly clear of the edge of the opening to permit the closure member to be removed. The engagement of the clamping members 14 with the wedges 13 causes the closure member to be drawn outwardly clamping the outer portion of the packing ring 9 tightly between the stiffening bead 3 of the drum wall and the marginal flange 7 of the closure member, forming a fluid tight seal between the closure member and the wall of the drum entirely around the opening. The location of the clamps at the corners of the closure members enables the closure member to be held to its seat with substantially uniform pressure throughout its periphery and since the wear plates are positioned on rigid parts of the drum, the clamping of the cover does not cause a distortion of the cylindrical sheet metal wall. The closure member is provided with a suitable handle 18 and with a recess 19 beneath the handle to accommodate the hand. The opening in the periphery of the drum is preferably elongated and extends longitudinally of the drum. When the closure member is released from the drum it can be lowered into the drum clear of the opening

and tipped inwardly and turned laterally so that it can be readily removed through the opening. To again put the closure member in place the closure member is inserted endwise into the drum, then turned parallel to the wall whereupon it can be lifted into engagement with the opening and clamped in place by means of the clamping members 14.

Having described my invention, I claim:

1. The combination with a washer drum having an elongated opening in its cylindrical wall intermediate the ends thereof, of a unitary closure member having a body portion adapted to fit in the opening and having a curvature corresponding to the curvature of the cylindrical wall, said cover having an inwardly offset marginal portion adapted to engage the interior of the drum around the edge of the opening, and a plurality of clamping members, each pivoted upon the outer side of the closure member adjacent the edge thereof and movable into and out of engagement with the wall of the drum adjacent the opening.

2. A washer drum having an elongated opening in its cylindrical wall intermediate the ends thereof, a closure member for said opening having a body portion adapted to fit within the opening and to complete the cylindrical wall, said closure member having an inwardly offset marginal portion adapted to engage the inside of the drum around the opening, said closure member being removable through the opening, wedge plates upon the outer surface of the drum adjacent the opening, and clamping members pivotally mounted upon the outer side of the closure member and movable laterally about their pivots into engagement with said wedge plates to draw the marginal portion of the closure member into tight engagement with the inside of the drum.

3. A washer drum having a sheet metal cylindrical wall provided with an elongated opening intermediate the ends thereof, the sheet metal at the edge of the opening being rolled over to provide a hollow tubular stiffening bead extending around the opening, and a closure member for said opening having a body portion adapted to fit within the opening, a marginal flange adapted to underlie the bead and clamping members engageable with the outside of the drum to draw the marginal flange into tight engagement with the inside of the drum.

4. A washer drum having a cylindrical sheet metal wall provided with an opening therein intermediate the ends thereof through which access may be had to the interior of the drum, the sheet metal of the drum wall at the edge of the opening being rolled over to form a hollow tubular stiffening bead surrounding the opening, a one-piece sheet metal closure member having an

- inturned marginal portion adapted to fit within the opening and an edge flange projecting outwardly from the inturned edge portion, a packing strip carried by said flange between said flange and the stiffening bead, and means for clamping the closure member in place and for drawing the marginal flange thereof into tight engagement with the packing.
5. A washer drum having a cylindrical sheet metal wall provided with an opening therein intermediate the ends thereof through which access may be had to the interior of the drum, the sheet metal of the drum wall being rolled over to form a hollow tubular stiffening bead surrounding the opening, an elastic packing enclosed within said bead, a one-piece sheet metal closure member having a body portion adapted to fit within said opening and having a marginal flange offset inwardly and adapted to underlie the stiffening bead, a packing strip carried by said flange and engageable with the inner side of the bead, wedge plates secured upon the outside of the drum and overlying the stiffening bead at the edge of the opening, clips pivoted upon the outside of the closure member and engageable with said wedge plates to draw the marginal portion of the closure member into sealing engagement with the stiffening bead at the edge of the opening.
6. The combination with a washer drum having its cylindrical sheet metal wall provided with an opening intermediate the ends thereof through which access may be had to the interior of the drum, the sheet metal at the edge of the opening being rolled back upon itself to provide a continuous tubular bead of a closure member for said opening having a body portion adapted to fit in said opening and an inwardly offset marginal flange extending outwardly therefrom and adapted to underlie the bead, a rubber packing ring mounted upon said flange said ring having a groove extending from the inner side thereof adapted to receive the flange

and a concave face adapted to fit against said bead, and releasable clamping means for securing the cover in place.

7. A washer drum having its peripheral wall formed of sheet metal and provided with an opening through which access may be had to the interior of the drum, the sheet metal at the edge of the opening being rolled back upon itself to form a continuous tubular bead, a rubber ring enclosed within said bead, spaced wedge plates secured upon the outside of the drum and overlying the bead at the edge of the opening, a one piece sheet metal closure member having a body adapted to fit within the opening and an inwardly offset outwardly extending marginal flange, a rubber packing ring having an upper face formed to fit the inner side of the bead and a groove in which the marginal flange of the closure member is received, and pivoted clips mounted upon the outer side of the closure member and adapted to be turned into engagement with the wedge plates to clamp the closure member in fluid tight engagement with the wall of the drum and to be turned back upon the closure member to release the same.

8. A washer drum having heads and a cylindrical sheet metal wall, said cylindrical wall having an elongated opening extending lengthwise thereof from adjacent one head to adjacent the other, said opening having rounded ends, a sheet metal closure member having a shape corresponding to that of the opening, said closure member having a marginal flange adapted to underlie the wall around the opening, wear plates secured upon the cylindrical wall adjacent the rounded corners of the opening, and an adjustable clamping member carried by the closure member adjacent each of the corners thereof, said clamping members being engageable with the wear plates to secure the closure member in place.

In testimony whereof, I hereunto affix my signature.

HARRY W. MITCHELL.
